UNITED STATES PATENT OFFICE.

HENRY F. ERICHSEN, OF CHICAGO, ILLINOIS.

DESIGN FOR AN EMBLEM FOR A RELIGIOUS SOCIETY.

46,207.

Specification for Design.

Patented Aug. 4, 1914.

Application filed May 28, 1914. Serial No. 841,662. Term of patent 7 years.

To all whom it may concern:

Be it known that I, HENRY F. ERICHSEN, a citizen of the United States, residing at Chicago, in the county of Cook and State of Illinois, have invented a new, original, and ornamental Design for an Emblem for a Religious Society, of which the following is a specification, reference being had to the accompanying drawing, in which a plan view of the design is shown.

I claim:

The ornamental design for an emblem for a religious society, as shown.

In testimony whereof I affix my signature, in the presence of two witnesses.

HENRY F. ERICHSEN.

Witnesses:

G. A. WINTERLEIBNER,
I. E. SMITH.
